(57) CLAIM

The ornamental design for a football, as shown and described.

DESCRIPTION

FIG. 1 is a perspective view of a football showing my new design;

FIG. 2 is a side view of the football shown in FIG. 1;

FIG. 3 is a view of the side opposite FIG. 2;

FIG. 4 is the bottom view of the football shown in FIG. 1;

FIG. 5 is the top view of the football shown in FIG. 1;

FIG. 6 is an end view of the football shown in FIG. 1; and,

FIG. 7 is a view of the end opposite FIG. 6.

The broken lines showing portions of the football or its environment in FIGS. 1-3 and 5-7 are for illustrative purposes only and form no part of the claimed design.

1 Claim, 4 Drawing Sheets
